UNITED STATES PATENT OFFICE.

MARTIN L. BEISTLE, OF SHIPPENSBURG, PENNSYLVANIA.

EXPANSIBLE TISSUE-PAPER ORNAMENT.

Application filed May 10, 1926. Serial No. 108,072.

This invention relates particularly to an ornamental ship in which a flat base member is provided with a single tissue paper member expansible to form the hull of the ship, the hull having a straight keel. The base member also carries sails interlocked with the base in such a manner that they will become disengaged only after deliberate manual manipulations, the interlock permitting the sails to fold perfectly flat against the base.

While I have disclosed a preferred embodiment of the invention for purposes of illustration it should be understood that various changes may be made in the structure without departing from the spirit and scope of the invention as hereinafter defined and claimed.

In the drawings:
20 Fig. 1 is a perspective of an ornamental ship embodying the invention;

Fig. 2 is a plan view of the base member, parts being broken away;

25 Fig. 3 is a bottom view of the ship in folded condition;

Fig. 4 is a section on line 4-4 of Fig. 5;
Fig. 5 is a section on line 5-5 of Fig. 4;

30 Figs. 6 and 7 are plan views illustrating the connection between the sails and the base member;

Figs. 8 and 9 are details of the support members;

Fig. 10 is a plan view of a sail member.

The base member 10 is a flat piece of card-board or other suitable material cut out and printed to represent the hull and rigging of a ship as shown in Figs. 1 and 2. A relatively wide notch 11 is cut into the lower edge of the base member, the front edge 12 and rear edge 13 of the notch being straight vertically, while the bottom of the notch is convex as at 14. A hull-forming member 15 of expansible cellular tissue is bent around the front edge 12 of the notch and has its lower fold 16 attached to opposite sides of the same part of the base as clearly shown in Figs. 2 and 3. The upper fold 17 of member 15 has support members 18 and 19 secured thereto on opposite sides of the base member. In order to expand the hull member 15 the ends of support members 18 and 19 are moved along lines 20 and 21 of Fig. 3 into contact with opposite sides of portion 22 of the base, thereby moving the fold 17 across the notch 11 and bending it around the end 13 of the

notch. This movement expands the member 15 to form the hull of the ship as shown in Fig. 1. When the parts are in this position the hook member 23 formed on support member 18 engages a hook 24 on the base, and a hook 25 on support member 19 is placed in a notch 26 on member 18, thereby holding member 15 in expanded condition.

It will be seen from Fig. 5 that as the expansible member 15 is moved across the notch 11 the cells in the center of the notch are subject to more lateral stretching than the cells nearer the ends of the notch, and hence if the bottom of the notch were straight the keel of the expanded hull would be hogged. By making the bottom of the notch convex this hogging tendency is overcome and the keel is kept straight, providing a flat bottom to enable the ship to stand alone on a plane surface.

The sails 27 are formed to simulate those of a square-rigged ship and are secured at right angles to the keel of the ship in a 80 manner now to be described. A slot 28 is formed in the rigging in the position to be occupied by the sail. A cut 29 extends through the base member from the outer edge of the base and leads diagonally to one 85 side of the slot at a point spaced from the upper end 33 of the slot. A second diagonal cut 30 leads from the opposite side of slot 28 at a point spaced from the lower end 34 of the slot. It will be clear from Figs. 2 and 90 7 that the slots 29 and 30 form hook members 31 and 32, the slots being so disposed that the upper hook member 31 is longer than the lower hook member 32. A vertical slot 35 (Fig. 7) is cut into the upper edge of the said member 27, and a similar slot 36 is cut into the lower edge of the sail member, leaving a solid portion 37 lying between the slots.

In securing the sail in its place on the base member the portion 37 of the sail is first passed down cut 29, through slot 28 and into cut 30 until it reaches the position of Fig. 6. The upper end of portion 37 is then clear of hook 31, and the portion 37 is thereafter moved upwardly toward the end 33 of slot 28 until the lower end of portion 37 is clear of hook 32. The portion 37 is now allowed to move down against the lower end 34 of slot 28 to the position of Figs. 116 1 and 7. Since the upper hook 31 is longer than the lower hook 32 it will be seen that

the hook 31 extends around the upper end of portion 37, while gravity holds portion 37 against the bottom of slot 28 and in engagement with hook 32. The cuts 29 and 30 are normally held closed by the resilience of the cardboard and must be opened manually to permit passage of the sail member. This structure prevents the sail from becoming disengaged from slot 28 unless it is purposely raised from the bottom of the slot and passed through the assembling steps in reverse order. This form of engagement, which is used for each of the sails, allows the sails to fold perfectly flat for shipping and also permits them to assume a natural position across the keel line when the ship is in display condition.

I claim:

- 20 1. In an ornamental structure, a base member having a wide notch formed in one side thereof, and a member of expandible tissue bent around one end of the notch and secured to the base member.
- 25 2. In an ornamental structure, a base member having a notch formed in one side thereof, and a member of expandible tissue extending through the notch and attached to antipodal parts of the base.
- 30 3. In an ornamental structure, a base member having a wide notch formed in one side thereof, and a folded member of expandible tissue attached to the base adjacent one end of the notch and adapted to be expanded across the notch.
- 35 4. In an ornamental structure, a base member having a notch formed in one side thereof, a member of expandible tissue extending through the notch, the lower fold of the expandible member being secured to antipodal parts of the base.
- 45 5. In an ornamental structure, a base member having a notch formed in one side thereof, a member of expandible tissue extending through the notch, the lower fold of the expandible member being secured to antipodal parts of the base, the upper fold of the expandible member having support members secured thereto.
- 50 6. In an ornamental structure, a base member having a notch formed in one side thereof, a member of expandible tissue extending through the notch and bent around one end of the notch, the lower fold of the expandible member being secured to antipodal parts of the base, the upper fold of the expandible member being adapted to be carried across the notch and bent around the opposite end of the notch.
- 60 7. In an ornamental structure, a base member having a notch formed in one side thereof, the bottom of the notch being convex, and a member of expandible tissue extending through the notch and secured to the base member.
- 65 8. In an ornamental structure, a base mem-

ber having a notch formed in one side thereof, the bottom of the notch being convex, and a member of expandible tissue extending through the notch and secured to antipodal parts of the base.

70

9. In an ornamental structure, a base member having a notch formed in one side thereof, the bottom of the notch being convex, and a member of expandible tissue extending through the notch and adapted to be expanded across the notch.

75

10. In an ornamental structure, a base member having a slot formed therein, a diagonal cut leading from the edge of the base member to the slot, a second member having slots extending inward from opposite edges and a solid portion lying between the slots, the second member being adapted for insertion through the diagonal cut into the slot in the base member, with the said solid portion of the second member positioned within the slot in the base member.

80

11. In an ornamental structure, a base member having a slot formed therein, a diagonal cut leading from the edge of the base member into the slot at a point spaced from one end of the slot, a second cut leading from the slot at a point spaced from the opposite end thereof, and a member adapted to be passed into both of said cuts during the process of inserting it into the slot.

85

12. In an ornamental structure, a base member having a slot formed therein, a diagonal cut leading from the edge of the base member into the slot at a point spaced from one end of the slot, a second cut leading from the slot at a point spaced from the opposite end thereof, and a second member having slots extending inward from opposite edges and a solid portion lying between the slots, the second member being adapted to be passed into both of said cuts during the process of inserting it into the slot, the aforesaid solid portion lying within the slot when the parts are in assembled position.

90

13. In an ornamental structure, a base member having a slot formed therein, a diagonal cut leading from the edge of the base member into the slot at a point spaced from one end of the slot, a second cut leading from the slot at a point spaced from the opposite end thereof, and a second member having slots extending inward from opposite edges and a solid portion lying between the slots, the second member being adapted to be passed into both of said cuts during the process of inserting it into the slot, the aforesaid solid portion lying within the slot and extending substantially the full length of the slot when the parts are in assembled position.

95

14. In an ornamental structure, a base member having a slot formed therein, a second member having a solid portion lying within the slot, the base member being

100

110

115

120

125

130

formed with hooks extending around each end of the solid portion.

15. In an ornamental structure, a base member having a vertical slot formed therein, a second member having a solid portion lying within the slot and extending substantially the full length of the slot, the

base member being formed with hooks extending around each end of the solid portion, the upper hook being longer than the lower hook.

In testimony whereof I affix my signature.

MARTIN L. BEISTLE.
